Application February 7, 1940, Serial No. 317,622

9 Claims. (Cl. 178—7.5)

This invention relates to television receivers and is particularly concerned with such receivers adapted to receive a carrier wave which is amplitude-modulated with video signals and frequency-modulated with synchronizing signals. This application is a continuation-in-part of applicant's copending application Serial No. 212,691, filed June 9, 1938, now Patent No. 2,254,435, granted Sept. 2, 1941.

In accordance with present television practice, there is developed and transmitted a signal which comprises a carrier wave modulated during successive intervals or trace periods by video-frequency signal components representative of light and shade values of an image being transmitted. During retrace intervals between the trace periods, the carrier wave is modulated by synchronizing impulses or components which correspond to initiations of successive lines and fields in the scanning of the image. At the receiver, a beam is so deflected as to scan and illuminate a target in a series of fields of parallel lines, the video-signal components being utilized to control the intensity of the beam. The line-scanning and field-scanning synchronizing components are separated from the video-signal components and from each other and are utilized to synchronize the operation of the receiver line-scanning and field-scanning apparatus with similar apparatus utilized at the transmitter in developing the signal. The transmitted program or image is thereby reconstructed on the target of the receiver.

Various types of television signals as well as various types of scanning and synchronizing methods and apparatus have been proposed. For example, in certain systems, negative modulation is employed, that is, a decrease in carrier amplitude during the trace periods when the carrier is amplitude-modulated by the video-signal components corresponds to an increase in illumination. In other systems, positive modulation is utilized in which an increase in carrier amplitude corresponds to an increase in illumination. The synchronizing-modulation components of the signals used in these systems ordinarily have amplitude values outside the range of the video-modulation components. Where negative modulation is employed, they are represented by increases in carrier amplitude while, where positive modulation is employed, they are represented by decreases in carrier amplitude, in either case usually having amplitude values corresponding to "blacker than black."

In present practice with negative modulation, synchronizing-signal components of the transmitted wave represent an increase in transmitted power of approximately 55 per cent over the maximum power required for the video-signal components alone. This is undesirable, not only because of the uneconomical requirement of in-

creased power, but also due to the fact that interference presented by the signal of one program with another is a function of the peak value of the power radiation of the signal of the interfering program.

In television receiving systems noise components disturb both the video-signal and the synchronizing-signal components. In general, noise impulses are represented by increases in carrier amplitude so that in positive modulation systems, the noise components appear in the image as white spots while in negative modulation systems they appear as black spots. The white spots are usually the more annoying to an observer so that, as far as the video signal is concerned, a negative modulation signal is less affected by noise. On the other hand, with negative modulation, synchronizing components are represented by increases in carrier amplitude and are thus most subject to noise effects, while with positive modulation, synchronizing components are represented by a reduction of carrier amplitude, usually to zero, so that they are substantially less affected by noise. Therefore, as far as the synchronizing components are concerned, a positive modulation signal is less affected by noise.

In applicant's above-mentioned copending application, an improved television system is described utilizing a carrier wave having the desirable characteristics incident to negative modulation with respect to the video-signal components and including synchronizing components which are not appreciably affected by noise disturbances.

In accordance with the system of the copending application, there is provided a television broadcasting system which comprises a station for developing and transmitting a modulated-carrier wave and which includes means for developing suitable video-signal components and synchronizing-signal components. The carrier wave is amplitude-modulated in accordance with video-signal components during the trace intervals and is frequency-modulated in accordance with synchronizing-signal components during the retrace intervals. The carrier wave, for example, normally has a predetermined frequency and is shifted with respect to this frequency during the retrace intervals. A receiver for receiving and reproducing the transmitted wave includes means for amplitude-detecting the carrier wave to derive the video-signal components and means for frequency-detecting the carrier wave to derive the synchronizing-signal components.

The system specifically disclosed in such copending application is a single-sideband system in which relative equalization of all reproduced video-signal components is provided by locating the carrier at such point on the slope of the frequency-response characteristic of a selector of

the receiver that the carrier is transmitted with one-half the over-all gain of the fully-transmitted sideband, in accordance with the general practice in single-sideband systems. If such equalization is not provided, the low-frequency video-signal components adjacent the carrier wave and subject to double-sideband reception are reproduced with a relatively greater amplitude with respect to corresponding components of the televised picture than those subject to pure single-sideband reception, resulting in a distortion in the reproduced picture. However, in such a system, when the frequency of the carrier wave is shifted during the retrace interval to transmit synchronizing-signal information, there is an effective shift of the carrier wave on the sloping portion of the band-pass selector characteristics of the receiver, resulting in amplitude pulses which appear in the video-signal channel of the receiver during retrace intervals, thus rendering it difficult to stabilize the video-frequency signal of the receiver at a signal amplitude corresponding to a given actual shade value of the transmitted picture, preferably black.

It is an object of the present invention, therefore, to provide an improved television receiver adapted to receive a modulated-carrier wave including video-signal components amplitude-modulated on the carrier wave and synchronizing-signal components frequency-modulated on the carrier wave.

It is another object of the invention to provide a television signal receiver adapted to receive a modulated-carrier wave including video-signal components amplitude-modulated on the carrier wave and synchronizing-signal components frequency-modulated on the carrier wave in which the signal applied to the reproducing device of the receiver is stabilized at a predetermined amplitude level corresponding to a predetermined actual shade value of the transmitted picture, preferably black.

In accordance with the present invention, there is provided a television receiver adapted to receive a modulated-carrier wave including video-signal components amplitude-modulated on the carrier wave only during trace intervals and synchronizing components frequency-modulated on the carrier wave only during retrace intervals. The receiver comprises means for detecting and utilizing the frequency-modulated components of the received signal to synchronize the scanning operation of the receiver, means for deriving from the received carrier signal a carrier signal having a peak-amplitude level during the retrace intervals representative of a limiting shade value of the transmitted picture and amplitude-modulated by the video-signal components during trace intervals, and means including a reproducing device for detecting and utilizing the amplitude-modulation components of the derived carrier signal, the detected amplitude-modulation components being subject to variation in amplitude, in accordance with the received carrier-wave amplitude variations. Also, the means for detecting and utilizing the amplitude-modulated components of the received signal includes means for stabilizing the signal input to the reproducing device at an amplitude level corresponding to the above-mentioned limiting shade value of the transmitted picture.

In accordance with one preferred embodiment of the invention, the video signal is negatively amplitude-modulated on the carrier wave and stabilization is effected at the signal-amplitude

level corresponding to the actual black shade value of the transmitted picture.

In accordance with another preferred embodiment of the invention, the received video-signal components are positively amplitude-modulated on the signal-carrier wave and stabilization is effected at an amplitude level corresponding to the actual white shade value of the transmitted picture. Also, in accordance with a modification of the invention, means are provided in the receiver for relatively equalizing reproduced video-frequency components of the transmitted picture.

For a better understanding of the present invention, together with other and further objects thereof, reference is had to the following description taken in connection with the accompanying drawings, and its scope will be pointed out in the appended claims.

In the accompanying drawings, Figs. 1 and 2 are circuit diagrams, partly schematic, of complete television transmitting and receiving systems, respectively; while Figs. 3, 4, 5, and 6 are graphs illustrating certain operating characteristics of the systems shown in Figs. 1 and 2 to aid in the understanding of the invention.

Referring now more particularly to Fig. 1 of the drawings, the television transmitter there represented is generally similar to that of applicant's aforesaid copending application and circuit elements which are similar have identical reference numerals. Such television transmitting system comprises a signal-generating device 10 of any conventional design which may include a cathode-ray signal-generating tube having the usual electron gun, photosensitive target and line-scanning and field-scanning elements. There are also provided a line-scanning generator 12 and a field-scanning generator 13 with their output circuits connected directly to the line-scanning and field-scanning elements, respectively, of signal-generating device 10. In order to provide pedestal impulses for blocking out or for suppressing undesired impulses in, and ensuring the proper wave form of, the modulation signal developed by the generator 10, there is provided a pedestal-impulse generator 14 having its output circuit coupled to a control electrode of signal-generating device 10. Synchronizing-signal generating apparatus is provided for the transmitter of Fig. 1 in accordance with an arrangement to be hereinafter described in detail.

In order to synchronize the operations of the generators 12, 13, and 14 and the synchronizing-signal generating apparatus of the transmitter, there is provided a timing-impulse generator 15 having a plurality of output circuits coupled to the generators 12, 13, and 14. A modulation-frequency combining amplifier 16 is coupled to output circuits of signal-generating device 10 and pedestal generator 14. Connected in cascade to the output circuit of the amplifier 16, in the order named, are a video-frequency amplitude modulator 17 which is provided with a local or master oscillator 18, a single-sideband filter 19, a frequency changer 20, a heterodyne-frequency filter 21, a power amplifier 22, and an antenna system 23, 24.

Neglecting for the moment the details of the stages 19, 20, and 21 and the synchronizing-signal generating apparatus presently to be described, the system just described includes the apparatus of a television transmitting system of conventional design, those parts of the system illustrated schematically being of any well-known suitable construction so that a detailed descrip-

tion of the system and its operation is unnecessary herein. Briefly, however, the image of the scene to be transmitted is focused on the target of the cathode-ray tube of signal-generating device 10 in which a cathode ray is developed, accelerated, and also focused on the target. Scanning or deflection waves developed by the generators 12 and 13 are applied to the scanning elements of the signal-generating device 10 and serve to deflect the ray to scan successive series of fields of parallel lines on the target. Pedestal impulses developed by the generator 14 are applied to the control electrode of the tube of signal-generating device 10 to suppress or block out the beam during retrace portions of the scanning cycle and are applied to the modulation-frequency amplifier 16 to suppress undesirable impulses or transients developed in the system during the retrace intervals and to aid in obtaining the required wave form of the video-modulation signal.

The photosensitive elements of the target of signal-generating device 10 being electrically affected to an extent depending upon the varying values of light and shade at corresponding incremental areas of the image focused thereon as the cathode ray scans the target, a voltage of correspondingly varying amplitude is developed in the output circuit of the signal-generating tube and applied to amplifier 16. Suitable timing or synchronizing impulses are applied from generator 15 to the generators 12, 13, and 14 to maintain these generators in synchronism with either the master frequency, in case of direct camera shots, or the motion picture camera, in the case where such pictures are being transmitted. The video-signal components applied to the amplifier 16 are amplified therein and thereupon supplied to the modulator 17 wherein they are impressed on the carrier wave generated by the oscillator 18. The signal is translated from the modulator 17 to the power amplifier 22 by way of stages 19-21, inclusive, to be described herein-after, wherein the synchronizing-signal components are added to the carrier wave. The heterodyne-frequency filter 21 is of any suitable conventional type designed to pass either the difference or sum frequencies developed in frequency changer 20, preferably the latter. The resulting modulated-carrier wave is amplified in the power amplifier 22 and is thereupon impressed upon the antenna system 23, 24 for radiation.

Coming now to the portion of the transmitter provided for adding synchronizing components to the transmitted carrier wave, it will first be noted that, while the generators 12 and 13 develop waves of saw-tooth form indicated at the left of these generators and at their respective frequencies, they also usually generate, in accordance with well-known practice, rectangular impulse waves of the form shown at the right of these generators and of the same frequencies. These impulses are timed to fall within and have durations somewhat less than the line-retrace and field-retrace periods, respectively, the generated line-frequency pulses being of substantially greater amplitude than the generated field-frequency pulses, as illustrated. Generators 12 and 13 are provided with output circuits which are coupled to a control apparatus 29 for the purpose of shifting the frequency of the carrier wave impressed upon the frequency changer 29 from the filter 19. Control apparatus 29 includes an oscillator indicated generally at 30 and a frequency-adjusting network indicated generally at 75

31. Preferably, the oscillator is of the push-pull type comprising vacuum tubes 32 and 33 having their input circuits connected in push-pull relation by way of an inductance 34, a leak resistor 35, and a grid condenser 35a being connected in parallel between the mid-tap on the inductance 34 and the cathodes of the tubes. The anode circuits of tubes 32 and 33 are also connected in push-pull relation by way of an inductance 36 coupled to the inductance 34 as indicated by bracket M, a mid-tap on the inductance 36 being connected to the cathodes of the tubes by way of a suitable anode-voltage supply, such as a battery 37. The inductance 36 is normally sharply tuned to a fixed frequency by means of a condenser 38 or other suitable circuit arrangement such that the oscillations developed by the oscillator 30, when combined with the carrier wave developed by oscillator 18, produce a heterodyne component of the desired carrier frequency for transmission. An inductance 39 is coupled to inductance 36 and connected to the frequency changer 20 for the purpose of shifting the carrier frequency of the signal derived from the filter 19 in accordance with the frequency of the oscillations developed by the oscillator 30.

The frequency-adjusting network 31 preferably comprises a pair of vacuum tubes 40 and 41 having their control grids connected by way of resistors 42 and 43 to the output circuits of the line-scanning generator 12 and field-scanning generator 13 in parallel by way of condenser 44, which is effective to by-pass oscillation-frequency currents to ground. The control grids of tubes 40 and 41 are also connected by way of coupling condensers 45, 46 to their respective anodes which, in turn, are connected to the terminals of an inductance 47. The inductance 47 is connected in push-pull relation in the anode circuits of the tubes, a mid-tap thereof being connected to the tube cathodes by way of a suitable anode-voltage supply indicated by battery 48. The inductance 47 is inductively coupled to the inductance 36 of the oscillator frequency-determining circuit.

In considering the operation of the transmitter just described and referring first to frequency-adjusting network 31 which, it will be assumed, is excited from oscillator 30, it will be seen that, since the impedances of condensers 45 and 46 are high compared with those of resistors 42 and 43, the voltages across the resistors lead the voltage across the inductance 47 by a large angle and that the space currents of the tubes, being in phase with the tube input voltages, also lead the voltage across inductance 47 in corresponding degree. Hence, the system simulates an impedance having primarily capacitive reactance, the value of which varies in accordance with the grid-bias voltage applied to the tubes. Adjustment of the grid-bias voltage on the tubes 40 and 41, therefore, varies the effective reactance of the circuit 31 and, hence, the natural frequency of the oscillation circuit 36, 38 to which it is coupled.

Normally, the tubes 40 and 41 are biased beyond cutoff and remain so biased during the video-signal or trace periods, being rendered operative only during synchronizing or retrace periods when impulses from one or both of the generators 12 and 13 are applied thereto. Since the tubes 40 and 41 are cut off during the video-signal periods, the oscillation circuit 36, 38 maintains its own natural frequency during these periods. During the occurrence of the synchronizing impulses, however, the impedance reflected

into the oscillation circuit 36, 38 by the frequency-adjusting network 31 is varied in accordance with the line-frequency and field-frequency impulse voltages applied to the grids of the tubes 40 and 41 from the generators 12 and 13 so that the frequency of the oscillation circuit is shifted to a value dependent upon whether a line-frequency or a field-frequency pulse is applied to the input circuits of tubes 40 and 41.

The relationship of the line-synchronizing and field-synchronizing pulses is preferably as shown in Fig. 3 of the drawings in which the transmitted line-synchronizing signals are indicated as L and the transmitted field-synchronizing signals are indicated as F. The field-synchronizing pulses are of approximately half the amplitude of the line-synchronizing pulses but considerably longer in duration and preferably bear such relationship to the line-synchronizing pulses that pulses of the two types are never transmitted during the same time interval. The relationship of the succeeding field-synchronizing pulse to the line-synchronizing pulses in a double-interlaced scanning system is shown by the dotted-line pulse F'.

Since the oscillator 30 is coupled to the frequency changer 20, its output is mixed with the video-modulated carrier signal from the filter 19 and the sum and difference heterodyne-frequency components are developed in the output circuit of the frequency changer 20 in a well-known manner. Either the sum-frequency or the difference-frequency components are selected by the filter 21 and delivered to the power amplifier 22 to be broadcast. Therefore, the frequency of the selected heterodyne-carrier output of frequency changer 20 is maintained constant during the trace intervals but varied or shifted during the retrace intervals in correspondence with the frequency variations of oscillator 30, as described above. In Fig. 4, there is illustrated half of the envelope of the resultant amplitude-modulated carrier wave developed by the transmitting system. The video-frequency signal components are represented by the portions of the wave indicated at V, the portions representing line-retrace and field-retrace periods, during which the carrier is shifted or varied, as described with reference to Fig. 3, being indicated at L and F, respectively, and magnitudes of the frequency shifts of the carrier wave being represented by the pulses L and F of Fig. 3, as explained above.

Thus, the carrier wave developed in the output circuit of modulator 17 is amplitude-modulated by the video-signal components only during the trace-scanning periods and, during these periods, the frequency of the wave developed by generator 30 and supplied to frequency changer 20 is constant so that the carrier frequency of the signal output of frequency changer 20 is constant. During a portion of each line-retrace period an impulse from generator 12 is impressed on frequency-adjusting network 31, thereby to effect a predetermined deviation in the frequency developed by the generator 30 and, hence, in that of the carrier frequency of the signal developed in frequency changer 20, as indicated by the pulses L of Fig. 3. Preferably, this frequency deviation is many times the frequency of the line-synchronizing signals of the system and may be, for example, of the order of 2 megacycles for a carrier frequency of 50 megacycles. During a portion of each field-retrace period, on the other hand, an impulse from the generator 13 is applied to network 31, thereby to effect a different and lesser predetermined frequency deviation in

the frequency developed by oscillator 30 and, hence, in that of the carrier frequency of the signal output of frequency changer 20, as indicated by the pulse F of Fig. 3. Line synchronization of the system, as will be seen by the curves of Fig. 3, is not interrupted during field-retrace periods.

Referring now to Fig. 2, the system there illustrated comprises a receiver of the superheterodyne type for receiving and utilizing the signal developed by the transmitter of Fig. 1 or a modulated carrier wave including video-signal components amplitude-modulated on the carrier wave only during trace intervals and synchronizing-signal components frequency-modulated on the carrier wave only during retrace intervals. This receiver includes an antenna system 50, 51 to which there are connected in cascade, in the order named, a radio-frequency amplifier and frequency changer 52, an intermediate-frequency amplifier 53, an amplitude detector 54, a video-frequency equalizer 50, a video-frequency amplifier 55, a unidirectional or background component re inserter 51, and a cathode-ray signal-reproducing device 56. Preferably, as explained below, the stages 52 and 53 are designed for single-sideband reception. A line-scanning generator 57 and a field-scanning generator 58 are also coupled to the output of amplifier 53 by way of synchronizing-signal deriving apparatus 59 hereinafter described in more detail. The generators 57 and 58 are coupled to the scanning elements of signal-reproducing device 56 in a conventional manner and preferably include conventionally synchronizing circuits which are adapted to be controlled by synchronizing impulses developed by the apparatus 59. The circuits 50-58, inclusive, may all be of any conventional well-known construction so that detailed illustrations and descriptions thereof are deemed unnecessary herein.

Referring briefly to the general operation of the receiving system, however, television signals are selected and amplified and converted into intermediate-frequency signals in the radio-frequency amplifier and frequency changer 52, the intermediate-frequency signals being, in turn, selectively amplified in the intermediate-frequency amplifier 53 and delivered to the detector 54. The video amplitude-modulation components of the signal are derived by the detector 54 and are supplied through equalizer 50, the operation of which will be described in detail hereinafter, to the video-frequency amplifier 55, wherein they are amplified and from which they are supplied in the usual manner to a brilliancy-control electrode of signal-reproducing device 56, the signals being stabilized by background re inserter 51 in a manner to be hereinafter fully described.

The intermediate-frequency signal is also supplied from the amplifier 53 to the apparatus 59 wherein the synchronizing signals are derived, the line-synchronizing and field-synchronizing components being effectively separated from the video-frequency signals and from each other and applied to the control circuits of the generators 57 and 58 as will be hereinafter further explained. Saw-tooth current or voltage scanning waves are developed in the line-scanning and field-scanning generators 57 and 58 and applied to the scanning elements of the signal-reproducing device 56 to produce electric scanning fields, thereby to deflect the intensity-modulated cathode ray in two directions normal to

each other so as to trace successive series or fields of parallel lines on the target of the tube to reconstruct the transmitted image.

Referring now more particularly to the synchronizing-signal deriving apparatus 59, there is comprised therein an intermediate-frequency amplifier 60 to which line-scanning generator 57 is coupled through a line-frequency selector 81 and a rectifier and amplitude selector 83 and to which field-scanning generator 58 is coupled through a field-frequency selector 82 and a rectifier and amplitude selector 84. The line-frequency selector 81 comprises a double-tuned selector circuit 92, 93 and is effective to pass primarily the carrier wave when deviated by the line-synchronizing pulses L of Fig. 3, which selected wave pulses are rectified in rectifier and amplitude selector 83. Unit 83 comprises a diode rectifier having a load circuit having two time constants, due to the resistor-condenser combinations 95 and 96. The time constant of the combination is long relative to the period of the line pulses and serves to provide a bias for rectifier 94 so that proportional cutting of the signal from unit 81 is effected. Only the peaks of the rectified output of amplitude selector 83 are thus developed across the combination 96 and these peaks are utilized for synchronizing line-scanning generator 57, this portion of the amplitude range of the output of unit 83 comprising substantially only line-synchronizing signal information.

Similarly, field-frequency selector 82 is effective to pass primarily the carrier wave when deviated by the field-synchronizing pulses F of Fig. 3, which selected wave pulses are rectified by rectifier and amplitude selector 84. Only the peaks of the rectified output of amplitude selector unit 84 are utilized to synchronize field-scanning generator 58, which comprises substantially only field-synchronizing signal information.

In considering the operation of the system just described, it will be assumed that both the single-sideband filter 19 of Fig. 1 and the selector of intermediate-frequency amplifier 53 of Fig. 2, which may be of any suitable well-known design, have characteristics, such as is shown by curve A of Fig. 5, wherein the relative gain is plotted against frequency. The selector is designed to have a response characteristic which is substantially level or uniform over a wide frequency band and a mean frequency so related to the carrier frequency of the signal to be translated that this carrier frequency is located on the uniform portion thereof, as indicated at X in Fig. 5. The selectors thus pass the carrier wave and one complete sideband of its modulation components, a portion of the other sideband components being suppressed by the selectors. It will be seen that, inasmuch as the carrier frequency of the system is at all times located upon the uniform-response portion of the characteristic selective circuits of the system, there is substantially no amplitude change in the intermediate-frequency signal output of amplifier 53 due to the frequency shift of the carrier wave during the line-retrace and field-retrace intervals of the signal. Thus, amplifier 53 effectively comprises a means for deriving from the received carrier signal a carrier signal having a peak-amplitude level during the retrace intervals representative of a limiting shade value of the transmitted picture and amplitude-modulated by the video-signal components during retrace intervals. There-

fore, the video-frequency signal of the receiver of Fig. 2 is not subject to any spurious amplitude variation during the line-retrace or field-retrace intervals of the signal and the background re inserter or stabilizing unit 91 is effective to stabilize the signal input to signal-reproducing device 56 at a predetermined limiting shade value of the amplitude range of the actual transmitted signal, rather than upon the peaks of amplitude pulses which correspond to signal amplitudes outside the range of the transmitted shade values. For example, in a receiver adapted to receive video-signal components which are negatively amplitude-modulated on the received carrier, background re inserter 91 is effective to stabilize the signal input to signal-reproducing device 56 at an amplitude level thereof corresponding to the black shade value of the transmitted signal, rather than at some infra-black level as in conventional television systems. On the other hand, if the received video-signal components are positively modulated on the received carrier, background re inserter 91 is effective to stabilize the signal input to signal-reproducing device 56 at an amplitude level corresponding to the white shade value of the transmitted signal. If the receiver is adapted to receive such positively-modulated video signals, it is necessary that the scanning generators 57 and 58 also supply to signal-reproducing device 56 block-out pulses for causing the scanning beam to be blocked out during the retrace intervals of the system.

Background re inserter 91 may be of conventional form and comprise a diode 97 having a load circuit including resistor 98 which is effective, together with source 99, to provide a suitable operating bias for signal-reproducing device 56, the unidirectional component of amplifier 55 being blocked by condenser 96.

However, inasmuch as in the receiver of Fig. 2 the double-sideband components corresponding to the lower modulation-frequency components and adjacent the carrier frequency are translated with substantially the same gain as the pure single-banded components, the detector output at the lower modulation frequencies is greater than that at the higher modulation frequencies. Therefore, it is necessary to provide an equalizer 90 having a band-pass characteristic, substantially as represented by curve B of Fig. 6, which is effective relatively to equalize the reproduced video-frequency components of the transmitted picture. For this purpose, the relative gain of equalizer 90 between zero frequency and a frequency f_a , corresponding to the video-signal range over which double-sideband components are transmitted and received, is half that of the video-signal range f_a to f_b , which corresponds to that over which only single-sideband components are transmitted and received. Such a band-pass characteristic may be provided by including a selective attenuator circuit in equalizer 90. Thus, resistors 101 and 102 may constitute a potentiometer to halve the amplitudes of components in the frequency range zero to f_a , while condenser 103 is of such value that it by-passes resistor 101 and thus removes the attenuation for components in the frequency range f_a to f_b .

It will be understood that equalizer 90 may be omitted, providing a corresponding amplitude compensation is made in the video-frequency portion of the transmitter of Fig. 1. In such case, the received signal may still be sta-

bilized at an amplitude level corresponding to a predetermined shade value of the reproduced signal, in accordance with the present invention. The equalization required may thus be effected in the transmitter by locating the carrier frequency of the signal applied to single-sideband filter 19 on the sloping part of its characteristic, inasmuch as the frequency deviation utilized to transmit synchronizing signals is introduced in the transmitter circuit at a point succeeding filter 19 and, in such case, the frequency variation utilized to transmit synchronizing signals causes no amplitude variation which may later appear in the received and detected video-frequency signal.

While there have been described what are at present considered to be the preferred embodiments of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A television signal receiver adapted to receive a modulated-carrier wave including video-signal components amplitude-modulated on said carrier wave only during trace intervals and synchronizing components frequency-modulated on said carrier wave only during retrace intervals comprising, means for detecting and utilizing said frequency-modulated components to synchronize the scanning operation of said receiver, means for deriving from said received carrier signal a carrier signal having a peak-amplitude level during said retrace intervals representative of a limiting shade value of the transmitted picture and amplitude-modulated by said video-signal components during said trace intervals, and means including a reproducing device for detecting and utilizing said amplitude-modulation components of said derived carrier signal, said detected amplitude-modulation components being subject to variation in amplitude in accordance with received carrier-wave amplitude variations, said last-named means including means for stabilizing the signal input to said reproducing device at an amplitude level corresponding to said limiting shade value of the transmitted picture.

2. A television signal receiver adapted to receive a modulated-carrier wave including video-signal components amplitude-modulated on said carrier wave only during trace intervals and synchronizing components frequency-modulated on said carrier wave only during retrace intervals comprising, means for detecting and utilizing said frequency-modulated components to synchronize the scanning operation of said receiver, means for deriving from said received carrier signal a carrier signal having a peak-amplitude level during said retrace intervals representative of a limiting shade value of the transmitted picture and amplitude-modulated by said video-signal components during said trace intervals, and means including a reproducing device for detecting and utilizing said amplitude-modulation components of said derived carrier signal, said detected amplitude-modulation components being subject to variation in amplitude in accordance with received carrier-wave amplitude variations, said last-mentioned means including means for providing relative equalization of reproduced video-frequency components of the

transmitted picture and means for stabilizing the signal input to said reproducing device at an amplitude level corresponding to said limiting shade value of the transmitted picture.

5 3. A television signal receiver adapted to receive a modulated-carrier wave including video-signal components negatively amplitude-modulated on said carrier wave only during trace intervals and synchronizing components frequency-modulated on said carrier wave only during retrace intervals comprising, means for detecting and utilizing said frequency-modulated components to synchronize the scanning operation of said receiver, means for deriving from said received carrier signal a carrier signal having a peak-amplitude level during said retrace intervals representative of the black shade value of the transmitted picture and amplitude-modulated by said video-signal components during trace intervals, and means including a reproducing device for detecting and utilizing said amplitude-modulation components of said derived carrier signal, said detected amplitude-modulation components being subject to variation in amplitude in accordance with received carrier-wave amplitude variations, said last-named means including means for stabilizing the signal input to said reproducing device at the signal amplitude corresponding to said black shade value of the transmitted picture.

20 4. A television signal receiver adapted to receive a modulated-carrier wave including video-signal components positively amplitude-modulated on said carrier wave only during trace intervals and synchronizing components frequency-modulated on said carrier wave only during retrace intervals comprising, means for detecting and utilizing said frequency-modulated components to synchronize the scanning operation of said receiver, means for deriving from said received carrier signal a carrier signal having a peak-amplitude level during said retrace intervals representative of the white shade value of the transmitted picture and amplitude-modulated by said video-signal components during trace intervals, means including a reproducing device for detecting and utilizing said amplitude-modulation components of said derived carrier signal, said detected amplitude-modulation components being subject to variation in amplitude in accordance with received carrier-wave amplitude variations, said last-mentioned means including means for stabilizing the signal input to said reproducing device at the amplitude level corresponding to said white shade value of the transmitted picture, and means responsive to said synchronizing means to block out said reproducing device during the retrace interval of the scanning cycle.

25 5. A television signal receiver adapted to receive a modulated-carrier wave amplitude-modulated by video-signal components only during trace intervals and frequency-modulated by line-synchronizing pulses to a predetermined deviation only during line-retrace intervals and by field-synchronizing pulses to a deviation of lesser magnitude during field-retrace intervals comprising, a selective circuit responsive to said line-synchronizing carrier deviations, a selective circuit responsive to said field-synchronizing carrier deviations, means coupled to said first-mentioned selective circuit for deriving line-synchronizing signals for said receiver, means coupled to said last-mentioned selective circuit for deriving field-synchronizing signals for said receiver.

ceiver, means for deriving from said received carrier signal a carrier signal having a peak-amplitude level during said retrace intervals representative of a limiting shade value of the transmitted picture and amplitude-modulated by said video-signal components during said trace intervals, and means including a reproducing device for detecting and utilizing said amplitude-modulation components of said derived carrier signal, said detected amplitude-modulation components being subject to variation in amplitude in accordance with received carrier-wave amplitude variations, said last-mentioned means including means for stabilizing the signal input to said reproducing device at an amplitude level corresponding to said limiting shade value of the transmitted picture.

6. A television signal receiver adapted to receive a modulated-carrier wave amplitude-modulated by video-signal components only during trace intervals and frequency-modulated by line-synchronizing pulses to a predetermined deviation only during line-retrace intervals and by field-synchronizing pulses to a deviation of lesser magnitude during field-retrace intervals comprising, a selective circuit responsive to said line-synchronizing carrier deviations, a selective circuit responsive to said field-synchronizing carrier deviations, amplitude-selecting means coupled to said first-mentioned selective circuit for selecting amplitude values thereof above a predetermined value to derive line-synchronizing signals for said receiver, amplitude-selecting means coupled to said last-mentioned selective circuit for selecting amplitude values above a predetermined value to derive field-synchronizing signals for said receiver, means for deriving from said received carrier signal a carrier signal having a peak-amplitude level during said retrace intervals representative of a limiting shade value of the transmitted picture and amplitude-modulated by said video-signal components during said trace intervals, and means including a reproducing device for detecting and utilizing said amplitude-modulation components of said derived carrier signal, said detected amplitude-modulation components being subject to variation in amplitude in accordance with received carrier-wave amplitude variations, said last-mentioned means including means for stabilizing the signal input to said reproducing device at an amplitude level corresponding to said limiting shade value of the transmitted picture.

7. A television signal receiver adapted to receive a modulated-carrier wave including video-signal components amplitude-modulated on said carrier wave as partially double-sideband and partially single-sideband components only during trace intervals and synchronizing components frequency-modulated on said carrier wave only during retrace intervals comprising, means for detecting and utilizing said frequency-modulated components to synchronize the operation of said receiver, means for deriving from said received carrier signal a carrier signal having a peak-amplitude level during said retrace intervals representative of a limiting shade value of the transmitted picture and amplitude-modulated by said video-signal components during said trace intervals, means for detecting said amplitude-modulation components of said derived carrier signal, means coupled to said last-mentioned detecting means for translating amplitude-modulation components corresponding to double-side-

band reception with a relative gain of half that of components corresponding to single-sideband reception, said detected amplitude-modulation components being subject to variation in amplitude in accordance with received carrier-wave amplitude variations, means for reproducing said detected amplitude-modulated components, and means for stabilizing the signal input to said reproducing means at an amplitude level corresponding to said limiting shade value of the transmitted picture.

8. A single-sideband television receiver adapted to receive a modulated-carrier wave including double-sideband and single-sideband video-signal components relatively equalized at the transmitter and amplitude-modulated on said carrier wave only during trace intervals and synchronizing components frequency-modulated on said carrier wave only during retrace intervals comprising, means for utilizing said frequency-modulated components to synchronize the operation of said receiver, means for deriving from said received carrier signal a carrier signal having a peak-amplitude level during said retrace intervals representative of a limiting shade value of the transmitted picture and amplitude-modulated by said video-signal components during said trace intervals, means for detecting said amplitude-modulation components of said derived carrier signal, said detected amplitude-modulation components being subject to variation in amplitude in accordance with received carrier-wave amplitude variations, a video-frequency amplifier having a uniform gain over its frequency pass band for amplifying said detected amplitude-modulation components, means for reproducing said detected amplitude-modulated components, and means for stabilizing the signal input to said reproducing device at an amplitude level corresponding to said limiting shade value of the transmitted picture.

9. A television signal receiver adapted to receive a modulated-carrier wave including video-signal components amplitude-modulated on said carrier wave only during trace intervals and synchronizing components frequency-modulated on said carrier wave only during retrace intervals comprising, means for detecting and utilizing said frequency-modulated components to synchronize the scanning operation of said receiver, means for deriving from said received carrier signal a carrier signal having a peak-amplitude level during said retrace intervals representative of a limiting shade value of the transmitted picture and amplitude-modulated by said video-signal components during said trace intervals, and means including a reproducing device for detecting and utilizing said amplitude-modulation components of said derived carrier signal and including means for providing single-sideband equalization for video components so located as to cause no conversion of received frequency-modulation components to amplitude-modulation components, said detected amplitude-modulation components being subject to variation in amplitude in accordance with received carrier-wave amplitude variations, said means including said reproducing device including means for stabilizing the signal input to said reproducing device at an amplitude level corresponding to said limiting shade value of the transmitted picture.
